UNITED STATES PATENT OFFICE.

CHARLES W. DUNHAM, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

HOLDING DEVICE FOR INSTRUMENTS.

1,120,040.

Specification of Letters Patent.

Patented Dec. 8, 1914.

Application filed February 24, 1914. Serial No. 820,724.

To all whom it may concern:

Be it known that I, CHARLES W. DUNHAM, a citizen of the United States, residing at Swissvale, in the county of Allegheny and State of Pennsylvania, have invented certain new and useful Improvements in Holding Devices for Instruments, of which the following is a specification.

My invention relates to instruments having delicate movable members, and particularly to means for protecting the movable members of such instruments from injury due to jar or shock during shipment.

My invention is particularly well adapted for use with electrical instruments, such as relays, comprising a movable member and delicately adjusted contact fingers controlled thereby.

One feature of my invention is the provision of means for holding the movable member in an intermediate position in which, in the case of a relay, the contact fingers are disengaged from the contact members with which they coöperate, so that the adjustment of the fingers cannot be deranged during shipment, and also so that in case the instrument is installed without removing the protecting means, all circuits controlled by the instrument will be open.

I will describe one form of relay having applied thereto one form of protecting means embodying my invention and will then point out the novel features thereof in claims.

In the accompanying drawings, Figure 1 is a view showing in side elevation, partly sectioned, one form of relay having applied thereto one form of protecting device embodying my invention, and Fig. 2 is a view showing on a larger scale the screw 11 shown in Fig. 1.

Similar reference characters refer to similar parts in both views.

Referring first to Fig. 1, the relay here shown comprises a top plate 3 in which is mounted an electromagnet 1 whose pole-pieces 4 are located on the under side of the top plate. The pole-pieces carry brackets 5 in which is journaled an armature 2 adapted to be attracted toward the pole-pieces when the magnet 1 is energized, and to fall away therefrom by gravity when the magnet is not energized. Fixed to the armature 2 are

studs 6 of insulating material which carry contact springs 7, only one of which is shown in the drawing. This spring 7 carries a contact finger 7^a which is adapted to make and break contact with a fixed contact member 8^a mounted in the top plate 3, and it also carries another contact finger 7^b which is adapted to make and break contact with another fixed contact member 8^b also mounted in top plate 3. It is understood that the upper contact 7^a—8^a is closed when the armature 2 is attracted to the pole-pieces, and that the lower contact 7^b—8^b is closed when the armature falls away from the pole-pieces. The armature and contacts are inclosed in a casing comprising the top plate 3, a bottom plate 9, and a glass ring 10.

The contact fingers 7^a and 8^a are delicately adjusted when the relay is assembled, and unless some protecting device is provided this adjustment is apt to be destroyed by jars and shocks during shipment. The protecting device here shown is a screw 11 which is shown on a larger scale in Fig. 2. This screw has two threaded portions 12 and 13 of different pitches and different diameters; the armature 2 is provided with a tapped hole 15 having threads of the same pitch and same diameter as those of the larger portion 12 of the screw, and the bottom plate 9 is provided with a tapped hole 14 having threads of the same pitch and same diameter as those of the smaller portion 13 of the screw. As here shown, the pitch of threaded portion 12 is less than that of portion 13, that is, there are more threads per inch in portion 12 than in portion 13. Since the threaded portion 12 and the middle unthreaded portion of the screw are smaller in diameter than the portion 13, the first two portions will pass freely through the hole 14 in the bottom plate. The larger end of the screw is preferably provided with a slot 11^a to accommodate a screw driver.

The operation of the screw 11 is as follows: After the relay has been assembled, the screw is passed upwardly through the hole 14 and is turned a short distance into hole 15 in the armature, the armature being at its lowest position, that is, farthest away from the pole-pieces 4. The length of the middle unthreaded portion is such

- that when this has been done the threads 13 begin to catch in the threads of hole 14. As the turning is continued, the screw advances into both the armature and the bottom plate, but owing to the difference in pitches of the threads it advances more slowly into the armature than into the bottom plate, so that the armature is raised toward the pole-pieces. The turning is continued until the armature is suspended midway between its extreme positions, so that both contacts 7^a—8^a and 7^b—8^b are open, and the screw is then locked in position by a nut 17.
- 15 The hole 15 in the armature is preferably slightly larger than the threaded portion 12 of the screw, to permit the armature to swing on its pivot without causing the screw to bind.
- 20 It will be seen that during shipment there is no possibility of derangement of the adjustment of contact fingers 7^a and 7^b because it is impossible for these fingers to be jarred into engagement with member 8^a or 8^b. It
- 25 will also be seen that when the relay is installed in service, if the screw 11 is not removed, all circuits controlled by the relay will remain open and no damage can result. This feature is of particular importance in the case of relays employed in railway signaling, because if the screw is not removed, a false clear signal cannot be caused, as has sometimes been the case when protective devices have been employed
- 30 which hold the armature rigid with one set of contacts closed during shipment.
- If desired, the arrangement of screw threads on screw 11 may be reversed, the threads which enter the armature being of
- 40 greater pitch than those which screw into the bottom plate. Then in applying the screw the armature would be pressed up against the pole-pieces before starting the screw in the bottom plate, and the armature
- 45 would be drawn away from the pole-pieces because the screw would travel faster in the armature than in the bottom plate. The arrangement shown in the drawings is, however, preferable because if the armature is
- 50 forced too far by the screw it will be stopped by the pole-pieces and no harm will be done to the contacts, whereas with the alternative arrangement if the armature should be forced too far the spring 7
- 55 or the lower finger 7^b would be bent.
- Although I have shown and described only one form of protective device embodying my invention, it is understood that various changes and modifications may be
- 60 made therein within the scope of the appended claims without departing from the spirit and scope of my invention.

Having thus described my invention, what I claim is:

1. In combination, an instrument having 65 a movable member, an inclosing casing for said movable member, and means projecting into said casing for locking said movable member in an intermediate position.
2. In combination, an instrument having 70 a movable member, an inclosing casing for said movable member, a screw having two threaded portions of different pitches, a hole in the movable member provided with threads of the same pitch as those on one 75 portion of the screw, and a hole in the casing provided with threads of the same pitch as those on the other portion of the screw.
3. In combination, an instrument having 80 a movable member, an inclosing casing for 80 said movable member, a screw having two threaded portions of different diameters and different pitches, a hole in the movable member provided with screw threads of substantially the same diameter and the 85 same pitch as those on the smaller portion of the screw, and a hole in the casing provided with screw threads of the same diameter and same pitch as those on the larger portion of the screw. 90
4. In combination, an instrument comprising a movable member and contacts one of which is closed when the member occupies one position and another of which is closed when the member occupies another 95 position, and means for locking said member in an intermediate position in which both contacts are open.
5. In combination, an instrument having 100 a fixed part and a movable member, and means for locking said movable member to the fixed part in an intermediate position.
6. In combination, an instrument having a fixed part and a movable member, a screw having two threaded portions of different 105 pitches, threads associated with the movable member and having the same pitch as those on one portion of the screw, and threads associated with the fixed part and having the same pitch as those on the other portion 110 of the screw.
7. In combination, an instrument having a fixed part and a movable member, a screw, a hole in the fixed member provided with threads matching those on the screw, and 115 means for locking the movable member to the screw.

In testimony whereof I affix my signature in presence of two witnesses.

CHARLES W. DUNHAM.
